Primary Examiner — Michael A. Pratt*Assistant Examiner* — Wendy L Arminio(74) *Attorney, Agent, or Firm* — Taylor J. Ross(57) **CLAIM**

The ornamental design for a cap for bottle, as shown and described.

DESCRIPTION

FIG. 1 is a top, rear and left side perspective view of a cap for bottle showing our new design;

FIG. 2 is a bottom, front and left side perspective view thereof;

FIG. 3 is a top plan view thereof;

FIG. 4 is a bottom plan view thereof;

FIG. 5 is a left side elevation view, the right side elevation being a mirror image thereof;

FIG. 6 is a rear elevation view thereof;

FIG. 7 is a front elevation view thereof; and,

FIG. 8 is a cross-sectional view taken in the direction of line 8-8 shown in FIG. 3.
